(57) **CLAIM**

The ornamental design for a medical device interface connector, as shown and described.

DESCRIPTION

FIG. 1 is a perspective view of the medical device interface connector;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof;

FIG. 7 is a left elevational view thereof;

FIG. 8 is a perspective view of a medical device interface connector of FIG. 1;

FIG. 9 is a front elevational view thereof;

FIG. 10 is a rear elevational view thereof;

FIG. 11 is a top plan view thereof;

FIG. 12 is a bottom plan view thereof;

FIG. 13 is a right elevational view thereof; and,

FIG. 14 is a left elevational view thereof.

The features shown in broken lines depict environmental structures only and form no part of the claimed design. The features shown in dash-dot-lines show the bounds of the claim and do not form part of the claimed design.
